TROUSER AND SKIRT HANGER

Adolph E. Ullrich, Milwaukee, Wis.

Application December 13, 1947, Serial No. 791,487

1 Claim. (Cl. 223—96)

1

My invention refers to garment hangers and it has for its primary object to provide a simple, durable and inexpensive hanger, which may be manually adjusted to firmly grasp and hold in suspension, between clamping strips, either a thick or thin garment without straining the spring tension bite, irrespective of its cross sectional thickness.

The specific object of my invention is to provide a pair of fiber or wood garment clamping strips, having anchored thereto widely spaced, upwardly converging wire suspension legs, coiled about a loading bar, the legs being then folded downwardly, in loop form, with a horizontally positioned compression stretch, which stretch laps over the suspension legs.

One of the important features of the hanger, is the providing of a multiple locking latch or lever, the same being pivoted to one of the leg loop stretches, and having elbows therein, to form locking notches, which notches selectively engage the companion horizontal loop stretch of its associated leg.

Thus, in effect each garment engaging strip is compressed by the combined spring tension of three wire units, to insure the life of the hanger under various light or heavy load spring tension conditions.

With the above and other objects in view, which will appear as the description proceeds, the invention resides in the novel construction, combination and arrangement of parts, substantially as hereinafter described, and more particularly defined by the appended claim, it being understood that such changes in the precise embodiment of the herein disclosed invention may be made as come within the scope of the claim.

In the accompanying drawings is illustrated one complete example of the physical embodiment of the present invention constructed according to the best mode so far devised for the practical application of the principles thereof.

In the drawings,

Figure 1 represents a side elevation of a garment hanger embodying the features of my invention, parts being broken away and in section to more clearly illustrate the structural features.

Figure 2, a cross sectional view of the same, the section being indicated by line 2—2 of Figure 1.

Figure 3, a similar cross sectional view of the hanger in its open or neutral position, and

Figure 4, a plan view partly in section, as indicated by the line 4—4 of Figure 1.

Referring by characters to the drawing, 1—1 indicates a pair of fiber garment gripping strips, 55

2

the same being of such length, for shoulder supports, upon their upper walls which are tapered upwardly from their ends, to nest readily in a garment folded thereover. The inner walls of the strips are provided with standard strips of clamping fabric 1', whereby either trousers or other garments, may be firmly held between said strips, it being understood that the strips may readily clamp, for example, more than one pair of trousers or other garments therebetween.

As best indicated in Figure 1 of the drawings, the strips, intermediate their ends, are provided with converging sockets 2, for anchoring therein the ends of inwardly flared wire legs 3—3, it being understood that the sockets are treated with some adhesive material, prior to insertion of the leg ends therein.

The upper ends of the legs are coiled about a loading bar 4, which bar forms one stretch of a loop, that terminates with a suspension hook 4'.

As best indicated in Figures 2 to 4 inclusive of the drawings, each pair of legs 3, at their upper ends are coiled about the loading stretch 4, and thereafter the wires extend downwardly and are flared beyond the legs, the same being in the form of loops having lower horizontally disposed stretches 5—5', which stretches cross the flared legs 3—3.

As best indicated in Figures 2 to 4 inclusive, 30 the loop stretches 5', have pivoted thereto, the end extensions of a wire lock and release latch or lever 6, which lever is kinked intermediate its ends, to form elbows or gripping notches 6'—6'', for selective engagement with the horizontal stretch 5, of the leg loop, the said latch or lever is shaped by folding the wire upon itself and the bend or crotch 7, is flared outwardly to develop a finger gripping handle, which handle projects 35 beyond the hanger strips, when the same are in their closed position, as shown in Figure 2, whereupon said handle may be conveniently manipulated, it being understood that the garment shoulder supporting upper face of the strips may 40 be slightly cut away, in a curved line, to clear 45 said lever end 7.

As best shown in Figure 1, of the drawings, the legs 3, being flared at an angle and anchored intermediate the ends of the strips, will thus, 50 not only positively fasten said strips to the legs, owing to the spread, but due to their position, when the strips are closed under spring tension, they will firmly grip the crease of trouser legs, due to the fact that spring pressure upon said legs is positioned near the outer creased edges

of said trousers and the biting engagement will thus firmly secure the same.

From the foregoing description, when it is desired, for example, to insert a single pair of trousers between the clamping strips, and the same present a wide open mouth, as shown in Figure 3 of the drawings, the trousers can readily be inserted. To clamp same, the latched lever being in its neutral open position, can be grasped at its extension 7, followed by a manual downward pull, whereby the elbowed surface of the lever will ride over the loop stretch 5, until said stretch is pocketed within elbow notch 6', and the lever or latch, is then in its extreme closed position, whereby the strips 4—4' are brought snugly together to insure, what might be termed a thin line of fabric, being securely gripped for suspension.

It is apparent in the event that two pair of trousers are to be gripped or the waist line of one or two dresses, the jaws should be set for gripping the extra thickness, as indicated in dotted lines, Figure 3. To accomplish this gripping operation, the operator simply swings the latched lever part way downwardly, until the elbow or notch 6'', engages the loop reach bar 5, whereby the strips are only partially brought together and locked in this position, as indicated by dotted lines, Figure 3.

While I have illustrated the lock and release catch or lever, provided for two adjustments, with reference to the strips, it is apparent, in some instances, I may provide the lever with another set of notches, so as to permit, for example, three adjustments.

From the foregoing it will be noted that the entire hanger mechanism is fabricated from spring wires and, hence, when compression for locking the strips together occurs, all of the wire elements combine to present a positive spring gripping arrangement, which is distributed throughout the entire set of wire units.

I claim:

10 A garment hanger comprising a hook having a loop shank, the lower stretch of which forms a loading bar, a pair of garment holding strips, spring wire legs secured to the strips, the same being upwardly inclined and coiled about the load bar of the hook, each leg coil being extended downwardly and flared outwardly to engage the legs intermediate their length, and having a horizontally disposed connecting stretch forming a looped pressure jaw, a wire lever latch pivoted to one of the loop stretches, the same 20 being bent in elbow form to provide a plurality of gripping notches, selectively engageable with the other loop stretch whereby the spring pressure upon the strips is varied, the said lever latch terminating with a finger gripping extension.
